UNITED STATES PATENT OFFICE.

CHARLES F. PRESCOTT, OF BROOKLYN, NEW YORK, ASSIGNOR TO FRANKLIN RAILWAY SUPPLY COMPANY, A CORPORATION OF DELAWARE.

LATERAL-MOTION DEVICE FOR LOCOMOTIVES.

Application filed December 17, 1924. Serial No. 756,414.

This invention relates to lateral motion devices such as are now commonly used for locomotive driving or axle boxes such, for example, as are illustrated in my copending 5 application Serial No. 611,010, filed January 6th, 1923, now Patent No. 1,600,425, granted September 21, 1926.

The primary object of the present invention is to provide a lateral motion device of 10 efficient character and suitable strength which will accommodate itself to certain clearance conditions imposed by some special types of locomotives. The particular condition which I meet by the present invention 15 is found in locomotives which are provided with a driving connection or connections inside the frames. An example of such is found in a three cylinder locomotive with the third cylinder between the usual two side cylinders and adapted to drive one of the 20 ordinary driving axles thru the medium of a suitable connecting rod and a crank on said axle. In locomotives of this type it is, of course, obvious that former arrangements 25 of lateral motion devices cannot be employed because of the fact that the cross member between the two boxes of a given axle would interfere with the driving connections, i. e., the connecting rod and the crank, between 30 the third cylinder and said axle.

More specifically considered, therefore, my invention may be said to contemplate the provision of a substantially inverted U-shaped leverage means between the two boxes 35 of a driving axle with the base of the U extending upwardly inside the locomotive frames and arranged to straddle the aforesaid driving connections.

In connection with such an arrangement 40 it is the object of my invention to provide resistance levers which bear against the boxes, one at each side, and project upwardly inside of the locomotive side frames together with a connecting member extending between 45 the upper ends of such resistance levers.

A further object is the provision of means 50 for taking up wear so that the parts may always be held tight. Still another object of the invention is the provision of resistance levers of the character described which shall 55 be fulcrumed upon the driving boxes and which shall receive load from the spring saddle at a point inside their fulcras. A fur-

ther object is the provision of suitable stop means for preventing lateral return thrust 55 beyond normal position.

The foregoing together with such other objects as may appear hereinafter or are incident to my invention I obtain by means of a construction which is illustrated in 60 preferred form in the accompanying drawings, wherein:

Fig. 1 is a partial transverse section through a locomotive taken as indicated by the line 1—1 of Fig. 2; Fig. 2 is a section on the line 2—2 of Fig. 1; Fig. 3 is a fragmentary plan view illustrating certain details of construction with the spring saddle shown in section; Fig. 4 is a fragmentary view similar to the showing of Fig. 1 but illustrating 70 modifications of the invention; and Fig. 5 is another fragmentary view similar to that of Fig. 1 illustrating a further modification.

Referring to the drawings and particularly of Figs. 1, 2 and 3 it will be seen that I have shown the side frames 1 of the locomotive and the forward driving axle 2 with its wheels 3. This axle is mounted in the usual driving boxes 4 arranged for vertical and lateral movement in the pedestal jaws 5 of the frames 1. Below the jaws is the customary pedestal binder 6 and between the box and the jaws are the wear plates 7 and the wedges 8. The boxes have suitable faces 9 for engagement with the hub faces 10. 85 The foregoing represents usual practice and need not be described in any further detail.

The axle immediately behind the axle 2, which is the axle of the next pair of drivers, is provided with a crank 11 which is driven 90 by the connecting rod 12. The cylinder and piston for this crank are not illustrated as they form no part of this invention but it may be stated that they are located between the usual side cylinders of the locomotive at 95 the forward end, the connecting rod running back to the said crank over the axle 2. Such constructions while not common in practice are well known to those skilled in the art and more locomotives of this type are in the 100 process of manufacture in this country at the present time.

My improved lateral motion device will now be described. At the inside each box 4 is provided with projecting shelf-like lugs 105 or abutment means 13 and on the upper face

or surface with concave bearing seats 14, said lugs and said bearing seats cooperating to form spaced abutments against which the bell-crank resistance levers 15 are adapted to bear, the resistance levers being provided with a rounded projection 16 adapted to fit into the recess 14 and with an abutment or stop means 17 adapted to engage with the abutment 13. At the base the resistance levers are connected together by the member 18. The resistance levers, therefore, together with the connecting member 18 form a generally U-shaped lever member.

The load of the vehicle is transmitted to the boxes through the usual springs 19 and the spring saddle 20 adapted to straddle the upper rail of the frame 1. The outer leg of the saddle rests directly on the driving box but the inner leg rests upon the abutments 17 and the connecting member 18 of the resistance levers and it should be noted that this brings the point of support for the inside leg of the saddle to the inside of the pivoting point of the resistance levers, said point being located between the projection 16 and the recess 14.

A member 21 extends between the upper ends 22 of the resistance levers and between the upper edges of the frames 1, the member 21 being forked at the ends to provide the legs 23 which embrace the legs of the saddle 20. The member 21 is provided with the downwardly projecting lugs 24 against which the upper ends 22 of the resistance levers are adapted to abut and also with the downwardly projecting lugs 25 adapted to hook over or engage the upper outer edges of the frames 1.

The apparatus so far described which is particularly illustrated in Figs. 1 to 3 inclusive permits movement of but one axle box at a time, that is, only one box on an axle is permitted to move when the locomotive takes a curve. The operation is as follows: As the locomotive takes a curve with the left-hand wheel 3 to the outside the wheel is forced to the right so that the hub face 10 comes in contact with the face 9 on the box. The box then moves to the right and carries with it the resistance levers and the saddle 20. (The limit of movement of the box is the distance between its flanges 26 and the outside faces of the wear plate 7 and wedge 8 indicated by the character X.) Since the upper ends of the resistance levers pivot or bear against the lugs 24 and since such upper ends cannot move because of the fact that the lugs 24 are stationary due to engagement of lug 25 with the outside of frame 1, a rocking movement of said levers will, therefore, follow, the pivot point on the box, as before stated, being upon the projection 16. The abutment 17 will therefore be raised and with it the right hand leg of the saddle 20. (It will be understood, of course,

that in this description of the operation reference is made to the left-hand side of Fig. 1.) The superimposed weight of the vehicle is then carried upon the outside of the box on the one hand and the raised abutments 17 of the resistance levers on the other hand and it will therefore be seen that just as soon as the locomotive returns to a tangent stretch of track such weight will immediately rock the resistance levers 15 back to their normal position, the return thrust being stopped by the members 13 and 17. The box is thus brought back to its normal position.

Fig. 4 represents structure which is identical in operation with that of Figs. 1 to 3 with the exception that it shows means for taking up wear and keeping the parts snug. In this figure the upper ends of the resistance levers 15 are provided with rollers 27 adapted to abut against the adjacent face of the wedge 28 which latter is backed by the abutment 24 and made adjustable through the medium of the bolts 29 and nuts 30. By raising or lowering the wedge proper adjustment can be maintained at all times.

With the truck illustrated in Fig. 5 motion of the levers 15 can take place at both sides of the axle simultaneously. In this arrangement the member 21 is dispensed with and the upper ends of the resistance levers 15 are connected by means of the adjustable member 30 having ball and socket connections 31 with the levers.

It will be seen that my lateral motion device taken as a whole is composed of a substantially U-shaped leverage means arranged in an inverted position and adapted to straddle the inside driving connections represented by the crank 11 and connecting rod 12. The resistance levers 15 bear against or rest upon the boxes 4 and project upwardly inside the frames 1 of the locomotive in a manner which makes it possible for the cross or connecting members 21-30 to easily clear the said driving connections. The whole arrangement is exceedingly simple and rugged and can be easily applied and when applied is very effective in the performance of its purpose.

I claim:

1. A lateral motion device for locomotives comprising in combination with the driving boxes of an axle, a resistance lever bearing against each box and projecting upwardly inside the locomotive frame, a connecting member between the upper ends of said levers, and stop means on the boxes for preventing lateral return thrust beyond normal position.

2. A lateral motion device for locomotives comprising in combination with the driving boxes of an axle, a resistance lever for each box extending above the box inside

the locomotive frame, a connecting member between the upper ends of said levers, and stop means on the boxes for preventing lateral return thrust beyond normal position.

5. 3. A lateral motion device for locomotives comprising in combination with the driving boxes of an axle, a resistance lever for each box extending above the box inside the locomotive frame, a connecting member 10 between the upper ends of said levers, and adjustment means cooperating with said connecting member for taking up wear.

4. In a lateral motion device the combination 15 of the driving box and the locomotive frame, of a resistance lever fulcrumed on the driving box, and a spring saddle straddling the frame and transmitting load to the box inside and outside the frame with the inside leg resting on the lever inside its 20 fulcrum.

5. A lateral motion device for the boxes 25 of a locomotive axle comprising in combination with the locomotive side frames, a resistance lever for each box resting at spaced points thereon and projecting upwardly therefrom inside said frames, one of said 30 points constituting a fulcrum for the lever upon lateral motion of the box, and a connecting member between the frames bearing a fixed relation to the frames and providing fulcrums for the upper ends of the resistance levers upon lateral motion of the box.

6. A lateral motion device for the boxes 35 of a locomotive axle comprising in combination with the locomotive side frames, a resistance lever for each box projecting upwardly therefrom inside said frames, a connecting member between the frames and bear-

ing a fixed relation thereto and providing fulcrums for the said resistance levers, and 40 wedge adjustment means between a resistance lever and its point of bearing on the connecting member.

7. A railway vehicle lateral motion device comprising in combination with an axle 45 box and the vehicle frame, a resistance lever fulcrumed on the box, means for transmitting vehicle weight to one arm of said lever at a point to the inside of said fulcrum, and means for maintaining the other 50 arm of said lever in a fixed relation with respect to the frame upon lateral motion of the box.

8. A railway vehicle lateral motion device 55 comprising in combination with an axle box and the vehicle frame, a bell-crank resistance lever fulcrumed on the box and extending upwardly inside the frame, means for transmitting vehicle load to one end of said lever at a point inside said fulcrum, and 60 an abutment for the other end of said lever having a fixed relation with respect to the frame.

9. The combination of a railway vehicle 65 frame, an axle, independently movable axle boxes, a resistance lever bearing on each box and projecting upwardly inside the frame, and means for exerting resistance on said levers upon lateral movement of the respective box, said means cooperating with 70 the frame on the side where the box is moving.

In testimony whereof, I have hereunto signed my name.

CHAS. F. PRESCOTT.
